UNITED STATES PATENT OFFICE

EDWARD A. RUSSELL, OF CHICAGO, ILLINOIS, ASSIGNOR TO VAPOR CAR HEATING COMPANY, INC., OF CHICAGO, ILLINOIS, A CORPORATION OF NEW YORK

STEAM HEATING SYSTEM FOR RAILWAY CARS

Application filed December 16, 1929. Serial No. 414,281.

This invention relates to certain new and useful improvements in a steam heating system for railway cars, and more particularly to an improved form of control valve embodying means for draining the radiating pipes and valves when the valve or valves are left in any position of adjustment.

In a vapor car heating system, of the general type shown for example in the reissue patent to Gold and Russell, reissue No. 16,487, dated November 23, 1926, the car is provided with a pair of similar radiators or pipe loops, one or both of which may be used according to the amount of heat required in the car. The radiators are connected in tandem through a pair of similar control valves, the steam flowing through a vapor regulator, and thence through the valves and the pipe loops back to the regulator. When in service, one or both of the loops is maintained filled with steam or vapor at substantially atmospheric pressure. The valves are provided with drainage ducts, whereby when the valves are closed and steam is cut off from the pipe loops or radiators, the condensate forming in the radiators can drain out through the respective valves. If for any reason the valves are left in open position and the car is then taken out of service, the vapor in the radiator loops will condense, but in this position of the valves the so-called "central loop" consisting of a portion of the two radiator loops or coils will not have any outlet to the drainage ports. According to the present invention, means is provided for draining this portion of the radiator loops when the steam supply is cut off with the valves left in open position. This means consists of an auxiliary drainage port formed in one of the control valves and provided with a thermostatically operated valve for closing the port when the system is filled with vapor but automatically opening the port when the vapor condenses so that the condensate may drain out.

The principal object of this invention is to provide an improved means for draining a vapor heating system such as briefly described hereinabove and disclosed more in detail in the specifications which follow. 50

Another object is to provide an improved form of control valve for a vapor car heating system, embodying an auxiliary drainage port.

Another object is to provide an improved 55 form of temperature controlled drainage port for the control valve of a vapor heating system.

Other objects and advantages of this invention will be more apparent from the following detailed description of one approved 60 form of apparatus embodying the principles of this invention.

In the accompanying drawings:

Fig. 1 is a perspective view of the principal elements of the car heating system. 65

Fig. 2 is a horizontal section through the two control valves.

Fig. 3 is a vertical section through the control valve embodying the improved drainage 70 port, this view being taken substantially on the line 3-3 of Fig. 2.

Figs. 4 and 5 are views similar to Fig. 3 showing modified forms of thermostatic valves for the drainage port. 75

The radiating system embodies two similar control valves A and B which feed steam to the two similar radiators or pipe loops C and D respectively. The vapor regulator E receives steam from the main supply pipe or 80 train line F and delivers this steam in the form of vapor at substantially atmospheric pressure to the radiator loops. This vapor regulator E may be of the type disclosed in the Gold, et. al., patent hereinabove referred to. Steam flows from the train line F through pipe 1 into the vapor regulator wherein a thermostatically controlled valve governs the flow of steam from the vapor regulator through pipe 2 into the control 85 90

valve A. The steam or vapor, after flowing through one or both of the radiator loops C and D returns from valve B through pipe 3 to the vapor regulator E. This returned vapor acts upon a temperature responsive element in the vapor regulator to control the steam supply valve. When steam or vapor is returned to the regulator pipe 3 the temperature responsive element will act to close the valve, but in the absence of such returned vapor the valve will open to admit more steam to the system. In this manner sufficient steam will be admitted from the source of supply to keep the radiator filled with steam or vapor at substantially atmospheric pressure, but when the returned vapor reaches the vapor regulator it will automatically act to cut off the supply of steam to the radiators until more is required due to condensation in the radiators.

The two control valves A and B are in most essential respects identical, each comprising a casing divided by inner webs so as to form four separate chambers: an inlet chamber *a*, an outlet chamber *b*, a supply chamber *c*, and a return chamber *d*. The chambers of the valve A are indicated by the unprimed reference characters above noted, whereas the similar chambers of valve B are indicated by primed reference characters. A hollow central cylindrical valve casing 4 is provided with ports 5 communicating with each of the valve chambers, and contains a rotary valve member 6. The valve 6 is shown in its so-called "closed" position in solid lines in the valve A, whereas the similar valve 6 is shown in "open" position in solid lines in the valve B. The alternate positions of each of these valves are indicated in dotted lines in the two valves A and B. As shown in Fig. 2, the valve A is in closed position and the inlet chamber *a* is in communication through this rotary valve with the outlet chamber *b*, while the supply chamber *c* is in communication with the return chamber *d*. The valve B is in the open position so that inlet chamber *a'* communicates with supply chamber *c'*, and return chamber *d'* communicates with the outlet chamber *b'*. The valve members 6 are moved either simultaneously or individually from their closed to their open positions or vice versa by means of the crank arms 7 on the rotary shafts 8 projecting out through the valve casings 9.

The inlet pipe 10 of the radiator C leads from supply chamber *c* of valve A, and the return pipe 11 of radiator C leads back into the return chamber *d* of valve A. This radiator C in the form here shown consists of the two oppositely projecting lower pipe sections 12 and 13 which are connected by the upwardly looped end portions 14 and 15 with the upper pipe 16 extending longitudinally of the car. The other radiator unit D consists in a similar manner of inlet and return

pipes 17 and 18, the lower longitudinally extending pipes 19 and 20, and the upwardly looped end portions 21 and 22 connecting with the ends of the upper pipe 23. The inlet pipe 17 extends from supply chamber *c'* of valve B, and the return pipe 18 leads back into return chamber *d'* of valve B. The outlet chamber *b* of valve A is connected by pipe 24 with the inlet chamber *a'* of valve B. The supply pipe 2 from the vapor regulator E leads into the inlet chamber *a* of valve A, while the return pipe 3 leads from return chamber *b'* of valve B back to the vapor regulator.

In operation, assuming that the maximum heating capacity of the system is to be utilized, both valves 6 will be in open position, that is valve A will be shown in the dotted line position and valve B in the solid line position (Fig. 2). In this position of the valves steam will flow from the vapor regulator through pipe 2 to the control valve A, thence from inlet chamber *a* of this valve to the supply chamber *c* and thence through the radiating loop C and back into the return chamber *d* and outlet chamber *b* of valve A. The flow continues through the connecting pipe 24 to the inlet chamber *a'* of valve B and passes in a similar manner through the valve B and radiating loop D flowing out from outlet chamber *b'* and return pipe 3 back to the vapor regulator E. If the radiation is to be entirely cut off, both valves 6 are moved to the closed positions shown in solid lines in valve A and in dotted lines in valve B. The steam now flows from inlet chamber *a* of valve A directly into the outlet chamber *b*, thence through pipe 24 to the inlet chamber *a'* and outlet chamber *b'* of valve B and back through pipe 3 to the vapor regulator. The two radiator loops C and D are now entirely cut off from the source of steam supply. When a reduced heating effect is desired, the valves 6 may be adjusted as shown in solid lines in Fig. 2, that is with valve A closed and valve B open. The steam now flows directly through the inlet and outlet chambers of valve A and pipe 24 to the valve B, wherein the steam is diverted through the radiating loop D before passing back to the vapor regulator. The first pipe loop C is now out of service.

It will be apparent that drainage means must be provided for taking care of the condensate that will form in the system as the steam or vapor is condensed when the heat is radiated or conducted therefrom. The pipes leading from the vapor regulator to the inlet and outlet chambers of the two valves A and B can drain back to the vapor regulator where provision is made for taking care of the condensate. However, when the valves are in the closed position, the radiators are entirely cut off from the vapor regulator.

and means must be provided for permitting the condensate to drain out from the radiator loops and from the supply and return chambers of the valves. For this purpose a drainage port 25 is provided in the bottom disc 26 of valve member 6 which registers with a similar drainage port 27 formed in the bottom of the valve casing when the valve is in the closed position shown in valve A. When the valve is in the open position shown in valve B, the ports 25 and 27 are out of register with one another so as to close the drainage ports and prevent the escape of steam or condensate therethrough. It will now be apparent that when either valve is in the closed position (shown in valve A, Fig. 2) the condensate forming in the radiator and pipes leading thereto can flow back into the supply and return chambers *c* and *d* and thence out through the drainage port 25 in the rotary valve. In order to break the vacuum that would be formed within the radiator loop when the valve is closed and communication is cut off with the vapor regulator, a passage is formed in the rotary valve 6 consisting of a vertical passage 28 having an outlet 29 at its upper end leading into the connected chambers *c* and *d* and a passage 30 at its lower end formed in the valve disc 26 and communicating with an outlet port 31 formed in the bottom of the valve casing. When the rotary valve is in the open position shown in valve B, the passage 30 is out of communication with the port 31 and this air inlet passage is closed. The features just described provide a means for completely draining the radiating units when the valves are closed.

However, it sometimes happens that the valves will be left in the open positions (with the heat on) and the car will then be disconnected from a train, or the steam main F will be disconnected so that the source of steam supply will be cut off. In such an event the inlet and return pipes 10 and 18 and the portions of the radiators which normally drain thereinto will be in open communication with the inlet chamber *a* of valve A and the outlet chamber *b'* of valve B, and these portions of the system can drain out in the same manner as during the normal operation of the system. At this time, the so-called "central loop" of the radiating system will drain back into the return chamber *d* of valve A and the supply chamber *c'* of valve B. This portion of the radiating system consists of the pipes 11 and 13, and 17 and 19, and those portions of the end loops and upper piping that are so positioned as to cause the liquid to gravitate through these pipes back to the valve casings. It will be noted that the chambers *d* and *c'* are in communication with the chambers *b* and *a'* and the connecting pipe 24 but that no means is provided for draining any of this portion of the system when the valves are in the open position. It is the particular

purpose of the present invention to provide means for taking care of this emergency. A drainage port 32 is formed in the lower portion of the web 33 separating the chambers *a'* and *b'* of valve B, so that when this port is open the central loop of the heating system can drain through this port into the outlet chamber *b'* and thence through pipe 3 back to the vapor regulator. A valve is provided for automatically closing this port when the system is full of steam or vapor and it is desirable to prevent the flow of steam through the port 32. In the form shown in Figs. 2 and 3, the valve 34 is pivoted at 35 to the lower end of a lever 36 which is intermediately pivoted at 37 to a bracket 38 extending from web 33 into the inlet chamber *a'*. A thermostatic element 39 is interposed between web 33 and the upper end 40 of lever 36. When chamber *a'* is filled with steam or vapor, the thermostatic element 39 will expand and push out the upper end 40 of lever 36 causing the lower end of the lever to swing inwardly and move valve 34 to closed position, thus preventing the flow of steam through port 32. When the steam supply is cut off and the steam or vapor in chamber *a'* condenses, the member 39 will contract and valve 34 will be moved out of the entrance to port or passage 32 so as to permit the condensate to drain out into outlet chamber *b'* and thence back to the vapor regulator.

In the modification shown in Fig. 4, the valve 34 is carried at the lower end of a bimetallic thermostatic bar 41 which is anchored at its upper end 42 within the valve chamber. When the bar 41 is heated it will swing to the position shown in Fig. 4 and close the valve. When the steam condenses and the bar 41 cools it will swing back into chamber *a'* so as to open the valve 34. In the modification shown in Fig. 5, the valve 34 is formed at the inner end of a thermostatic rod 43 adjustably mounted at 44 in the outer wall of the valve casing. When bar 43 is heated by the presence of steam within the chamber *a'*, it will expand so as to move the valve 34 into the passage 32 and close the drainage port. When rod 43 again contracts, it will pull the valve 34 back so as to open the drainage port and permit the condensate to flow out.

It will now be apparent that this drainage port 32 will normally be closed when the car is in service and the steam supply is connected so as to maintain the chambers *a*, *b*, *a'*, and *b'* filled with steam or vapor. At any time the steam supply is cut off this port will automatically be opened. In case the valves are left in closed position, the port 32 will be unnecessary since the chambers *a'* and *b'* are now in open communication with one another through rotary valve 6. However, in the event that the valves 6 are left in open position, the port 32 will form a means for draining the central radiating loop and the chambers *b*, *d*, *c'* and *a'*. This auxiliary drainage

port 32, in combination with the normal drainage means first described, permits the radiating system to be completely drained of condensate under any and all conditions.

5. It is to be understood that it is only necessary to provide this auxiliary drainage port 32 in the second control valve, (the valve B) and that the drainage from the first valve A will be taken care of through the connecting 10 pipe 24. In all other respects, the valves A and B may be identical with one another.

As already noted, in normal operation all of the chambers a , b , a' and b' will be filled with steam so that the thermostatically operated valve can be positioned in any one of these chambers, and the valve opening 32 can be positioned in the web 33 of either valve A or B. It is only essential that the central loop of the radiating system be permitted to 20 drain out toward either the supply or return sides of the system.

I claim:

1. In a vapor heating system, a vapor regulator, a pair of similar control valves each 25 comprising a casing formed with inlet, outlet, supply and return chambers, a valve movable from open position in which the inlet chamber is placed in communication with the supply chamber and the outlet chamber in 30 communication with the return chamber, to closed position in which the inlet chamber communicates with the outlet chamber and the supply chamber with the return chamber, the valve being formed with a drain port for 35 the supply and return chambers which is open when the valve is closed and is closed when the valve is open, a supply conduit leading from the vapor regulator to the inlet chamber of the first valve, a conduit connecting the outlet chamber of the first valve with the inlet chamber of the second valve and a return conduit connecting the outlet chamber of the second valve with the vapor regulator, a pair of radiators one of which has its supply and return pipes connected with the supply and return chambers respectively of the first valve, and the other radiator of which is similarly connected with the second valve, the casing of one of the valves being provided with a drain port connecting the inlet and outlet chambers thereof, a valve controlling this port and 50 thermostatically operated means for automatically closing the valve when the chambers are filled with vapor.

2. In a vapor heating system, a vapor regulator, a pair of similar control valves each 55 comprising a casing formed with inlet, outlet, supply and return chambers, a valve movable from open position in which the inlet chamber is placed in communication with the supply chamber and the outlet chamber in communication with the return chamber, to closed position in which the inlet chamber communicates with the outlet chamber and the supply chamber with the return chamber, the valve 60 being formed with a drain port for the supply

and return chambers which is open when the valve is closed and is closed when the valve is open, a supply conduit leading from the vapor regulator to the inlet chamber of the first valve, a conduit connecting the outlet chamber of the first valve with the inlet chamber of the second valve and a return conduit connecting the outlet chamber of the second valve with the vapor regulator, a pair of radiators one of which has its supply and return pipes connected with the supply and return chambers respectively of the first valve, and the other radiator of which is similarly connected with the second valve, the casing of one of the valves being provided with a drain port connecting the inlet and outlet chambers thereof, a valve controlling this port and thermostatically operated means for automatically closing the valve when the chambers are filled with vapor.

3. In a vapor heating system, a vapor regulator, a pair of similar control valves each comprising a casing formed with inlet, outlet, supply and return chambers, a valve movable from open position in which the inlet chamber is placed in communication with the supply chamber and the outlet chamber in communication with the return chamber, to closed position in which the inlet chamber communicates with the outlet chamber and the supply chamber with the return chamber, the valve being formed with a drain port for the supply and return chambers which is open when the valve is closed and is closed when the valve is open, a supply conduit leading from the vapor regulator to the inlet chamber of the first valve, a conduit connecting the outlet chamber of the first valve with the inlet chamber of the second valve and a return conduit connecting the outlet chamber of the second valve with the vapor regulator, a pair of radiators one of which has its supply and return pipes connected with the supply and return chambers respectively of the first valve, and the other radiator of which is similarly connected with the second valve, the casing of one of the valves being provided with a drain port connecting the inlet and outlet chambers thereof, a thermstatic element positioned in one of these chambers and a valve movable to close the port when the thermstatic element is expanded by vapor in the inlet chamber.

4. In a vapor heating system, a vapor regulator, a pair of similar control valves each comprising a casing formed with inlet, outlet, supply and return chambers, a valve movable from open position in which the inlet chamber is placed in communication with the supply chamber and the outlet chamber in communication with the return chamber, to closed position in which the inlet chamber communicates with the outlet chamber and the supply chamber with the return chamber, a supply conduit leading from the vapor regulator to

the inlet chamber of the first valve, a conduit connecting the outlet chamber of the first valve with the inlet chamber of the second valve and a return conduit connecting the outlet chamber of the second valve with the vapor regulator, a pair of radiators one of which has its supply and return pipes connected with the supply and return chambers respectively of the first valve, and the other radiator of which is similarly connected with the second valve, the control valves being provided with a plurality of drainage ports for permitting condensate to flow from the radiators and valves in any position of adjustment of the valves, and means for automatically closing said ports when the system is filled with steam.

EDWARD A. RUSSELL.
